CLAIM

The ornamental design for an operator's cab for a work vehicle, as shown and described.

DESCRIPTION

FIG. 1 is a front perspective view of an operator's cab for a work vehicle showing our new design.

FIG. 2 is a front view thereof.

FIG. 3 is a rear view thereof.

FIG. 4 is a first side view thereof.

FIG. 5 is a second side view thereof.

FIG. 6 is a top view thereof.

FIG. 7 is a bottom view thereof; and,

FIG. 8 is a rear perspective view thereof, particularly illustrating an environmental view of the operator's cab for a work vehicle, such as a wheel loader.

The broken lines contained within the figures, including, but not limited to, any dash-dot broken lines and/or dash-dash broken lines, represent portions of the operator's cab for a work vehicle that form no part of the claimed design. Additionally, contour lines and/or surface shading are illustrated simply for purposes of highlighting the solid-rendering, and, thus, form no part of the claimed design.

1 Claim, 8 Drawing Sheets
